BOTTLE CAP

Joseph D. Tessier, Worcester, Mass.

Application September 3, 1943, Serial No. 501,045

6 Claims. (Cl. 215—38)

This invention relates to a bottle cap particularly for small neck bottles ordinarily used for beverages.

Objects of the invention include the provision of a bottle cap having manually operated means for applying the cap to a bottle to hermetically close the same, and also to remove the cap from the bottle; the provision of a bottle cap which is relatively simple in nature and easy to manufacture and yet is efficient in operation and positively prevents escape of gas in the bottle; the provision of a bottle cap as aforesaid which is easily applied to and removed from the neck of a bottle and which may be used indefinitely as it will not become deformed nor will it wear out no matter how long or often it is used.

Further objects of the invention reside in a bottle cap of the nature described, including a rotary finger piece which is turned in one direction to clamp the cap to a bottle and in the other direction to release the bottle cap.

Other objects and advantages of the invention will appear hereinafter, reference being had to the accompanying drawing, in which

Fig. 1 is a view in elevation of my new bottle cap;

Fig. 2 is an elevational end view;

Fig. 3 is a bottom plan view;

Fig. 4 is a plan view with the finger piece removed;

Fig. 5 is a bottom plan view of the finger piece; and

Fig. 6 is a side view of one of the clamping jaws.

My new bottle cap includes a rotary finger piece 10, a bottom bottle neck-receiving element 12 having a base 13 and a downwardly extending skirt 14 to receive the neck of the bottle, a pair of clamping jaws 16, and a screw 18. All the parts may be made in any desired way, and it is preferred that the finger piece 10 and the bottom element 12 should be made of plastic, although I do not limit myself to this material. The jaws 16 may also be made of plastic but preferably these jaws are of pressed metal.

The finger piece 10 is round and may be largely hollow or solid whichever is preferred. The bottom element 12 is also round, the skirt 14, however, being interrupted as at 20 at diametrically opposite points (see Figs. 3 and 4). At the side edges of the interruptions 20 there are outwardly extending elements 22 which may be used as finger grips if desired. The jaws 16, of which there are two, are exactly alike and may be made in the same die. Each jaw comprises a flat plate

24 which slides in a groove 28 in the top portion of the bottom element base 13. Each plate 24 has an enlarged portion 28 which is bent to a reverse angle as shown at 30, the angle portion 30 forming the gripping jaws which will be positioned under the pouring lip of a bottle when the jaws are brought together by means to be described.

The screw 18 projects upwardly from the bottom element 12 and passes through a pair of slots 32 in the corresponding edges of the plates 24 of jaws 16 and it will be seen that slots 32 permit relative sliding motion of the jaws in the direction of the arrow in Fig. 4. Each plate 24 has a lug 34 projecting upwardly therefrom for cooperation with eccentric grooves 36 located in the bottom of the finger piece 10. The screw 18 projects into a threaded hole 38 and locks the parts together.

20 In applying a bottle cap to a bottle the finger piece 10 is rotated to bring the angle elements 30 of the jaws 16 as far apart as possible and then the cap is placed over the neck of the bottle, the latter being received only in the bottom element 12. The finger piece is then reversely rotated to bring the jaws toward each other by means of slots 36 into which the lugs 34 project. The free ends of the jaws thus are projected under the pouring lip of the bottle and by a cam action 30 force the bottle neck into contact with the base. The friction of the parts will hold the jaws in clamped position so that the cap cannot be removed accidentally. Any ordinary beverage bottle will be accommodated by my bottle cap, it being noted that variation in the bottle will not detract from the efficiency of this invention because of the wide range of adjustment of the jaws. The finger piece 10 cannot be removed by turning it off the screw because the lugs 34 will prevent any unwarranted turning of the finger piece.

It has been found that bottles have variations as to their inside diameter, and therefore, the ordinary cork or stopper is very often of little effect. The outside diameters of bottles are of fairly uniform character, but they vary slightly and therefore it will be seen that in order to provide an effective bottle cap of this nature it is necessary to have a sufficient range of adjustment of the clamping pieces to accommodate various types of bottles.

Having thus described my invention and the advantages thereof, I do not wish to be limited to the details herein disclosed, otherwise than as set forth in the claims, but what I claim is:

1. A bottle cap for bottles having a pouring lip, said cap comprising a circular skirted bottle neck-receiving element having slots therein, a plurality of like jaws mounted for radial sliding movement relative to the element, each jaw being arranged to move in a slot, a rotary finger piece mounted on the skirted element and completely covering the same, cooperating means on the finger piece and jaws to move the latter into and out of bottle closing condition, and means on each jaw enclosed in the element and extending toward each other to grip under the pouring lip of the bottle.

2. A bottle cap comprising a bottle neck-receiving element including a circular flat base, a groove in the base, a pair of movable jaws in the groove, a circular finger piece rotatable on the element and effective to cover the jaws and base, a projecting lug on each jaw, eccentric grooves in the finger piece cooperating with the lugs to mutually retract the jaws or selectively to approach the jaws toward each other, a circular wall depending from the base, slots in the wall, and each jaw being arranged to move in a slot.

3. A bottle cap comprising a bottle neck-receiving portion including a circular base, a circular circumferential skirt depending therefrom

to receive the neck of a bottle, means providing interruptions in the skirt, a movable jaw element located in each interruption and constructed and arranged to move radially of the base in said interruptions, a rotatable finger piece, cam means on the jaws and finger piece cooperating to move the former toward each other or selectively apart, means mounting the finger piece on the base, said finger piece being circular and having a diameter substantially the same as that of the base and skirt, and having a height comparable to the length of the skirt, said finger piece completely overlying and concealing the cam means.

4. A bottle cap as recited in claim 3 including a groove in the base in which the jaws are received and confined to a rectilinear motion, said finger piece covering the jaws in the groove and preventing exit thereof.

5. A device as recited in claim 1 wherein said last named means each comprises a free-ended resilient tongue inclined with respect to the jaws.

6. A bottle cap as recited in claim 2 including inclined resilient gripping tongues on each jaw, said tongues extending toward each other, said circular wall extending below the tongues.

JOSEPH D. TESSIER.
